US0D1092030S

(12) **United States Design Patent** (10) **Patent No.:** **US D1,092,030 S**
(45) **Date of Patent:** **** Sep. 9, 2025**

(54) **SHOE**

- (71) Applicant: **adidas AG**, Herzogenaurach (DE)
- (72) Inventors: **John L. Hoeck, III**, Lake Oswego, OR (US); **Christopher N. Padilla**, Portland, OR (US); **Stephen P. Dobson**, Portland, OR (US); **Christian Manuel Arias Delgado**, Portland, OR (US); **Niccolo Dambrasio**, Portland, OR (US)
- (73) Assignee: **adidas AG**, Herzogenaurach (DE)

(**) Term: **15 Years**

(21) Appl. No.: **29/907,369**

(22) Filed: **Jan. 5, 2024**

(51) LOC (15) Cl. **02-04**

(52) U.S. Cl.

USPC **D2/972; D2/947**

(58) **Field of Classification Search**

USPC D2/902-912, 923, 924, 946, 947, D2/969-979
CPC A43B 1/0072; A43B 1/02; A43B 1/04; A43B 1/05; A43B 3/00; A43B 3/0036; A43B 3/02; A43B 3/04; A43B 3/14; A43B 5/00; A43B 5/02; A43B 5/06; A43B 5/10; A43B 11/00; A43B 15/00

Assistant Examiner — Caitlin Mackenzie Williams

(74) Attorney, Agent, or Firm — Sterne, Kessler, Goldstein & Fox P.L.L.C.

(57) **CLAIM**

The ornamental design for a shoe as shown and described.

DESCRIPTION

FIG. 1 is a front isometric view of a shoe showing the claimed design;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the shoe that form no part of the claimed design;

The dot-dash broken lines in the figures show boundaries that form no part of the claimed design.

1 Claim, 8 Drawing Sheets
